UNITED STATES PATENT OFFICE.

ANDREW D. DOWD, OF HOBOKEN, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

1,332,976.

Specification of Letters Patent. Patented Mar. 9, 1920.

Application filed June 6, 1918. Serial No. 238,494.

To all whom it may concern:

Be it known that I, ANDREW D. Dowd, a citizen of the United States, residing at Hoboken, in the county of Hudson, State of New Jersey, have invented certain new and useful Improvements in Signaling Systems, of which the following is a full, clear, concise, and exact description.

This invention relates to selective signaling systems and particularly to systems for transmitting combinations and permutations of current impulses for selectively actuating a plurality of electro-responsive devices at a receiving station.

15 The principal object of this invention is the provision of selectively operable switching means and impulse storage devices whereby a group or permutation of impulses may be stored pending transmission, thereby permitting the selective actuation of the switches for setting up a new character combination while the previously selected group or permutation of impulses is being transmitted.

20 25 A further object is to provide an efficient and reliable transmitting system whereby successive groups of impulses may be sent over a line circuit in rapid succession to effect the operation of suitable receiving mechanism.

30 35 For the accomplishment of the above objects the invention contemplates the employment of character determining means coöperating with signal storage devices, such as condensers or their equivalents, and means for connecting the signal storage devices sequentially with an electro-responsive device for controlling the line circuit. The electro-responsive device may comprise a 40 45 polar relay which responds to the impulses stored in the storage devices.

The above and other objects of this invention will be fully set forth in the following description and claims and will be more readily understood by reference to the accompanying drawing in which is disclosed one specific embodiment of the invention.

50 Referring to the drawing, A represents a keyboard transmitter comprising a plurality of character determining elements, which elements may be manually operated to determine the signals to be transmitted. B represents an automatic transmitter which may be controlled by a perforated tape or the like. The transmitters A and B, both of

which are well known in the art, may be of any suitable types. When the tape transmitter is employed, the switch contacts 15 to 23 inclusive are moved into engagement with their respective upper contacts, as shown in the drawing, and when the keyboard transmitter is employed, the switch contacts are moved away from their respective upper contacts and into engagement with their respective lower contacts. Any suitable means may be provided for moving the contact switches 15 to 23 inclusive from one position to another.

55 In series with the line or loop L is a tongue 50 of a polar relay 51 for controlling the condition of the line circuit. One terminal of the relay is connected through a potentiometer comprising a resistance 52 and battery 54 to ground, and the other terminal is connected to the sending common 70 ring 42 of the transmitting distributor 40. The arm 45 of the distributor 40 is frictionally mounted on a constantly rotating shaft and is adapted to be released and arrested automatically at the end of each 75 revolution, as will presently appear.

80 85 A plurality of condensers, 30, 31, 32, 33 and 34, are provided in which the signaling impulses representing the various characters may be stored prior to the transmission of the character combination. One terminal of each condenser is connected to ground and the other condenser terminals are arranged to be connected to a grounded 90 source of battery 53 through switch contacts 95 25 to 29 inclusive, which contacts are controlled by a charging magnet 44, switch contacts 15 to 20 inclusive, and transmitter contacts 10 to 14 inclusive or transmitter contacts 55 to 59 inclusive, depending upon 95 whether the automatic or keyboard transmitter is employed for setting up the character combinations. The condensers are selectively charged over the circuits including the above mentioned switch contacts, in 100 accordance with the selective action of the character determining elements of the transmitters. One terminal of each condenser is also connected to a segment of the transmitting distributor which in its operation dis-

105 charges the charged condensers and charges the uncharged condensers sequentially through the winding of the polar relay 51; that is, those condensers which have been selectively charged from battery 53 through 110

the transmitter contacts will be discharged by the operation of the distributor through the winding of relay 51, and those condensers which have been unaffected by the operation 5 of the transmitter contacts will be charged from battery source 54 through the winding of relay 51 and the respective segments of the distributor.

Thus, if it be assumed that the characters 10 are selected or the line circuit is closed by negative impulses, the polar relay will throw the tongue 50 into engagement with contact 41 when the condensers are discharged through the relay 51 and will throw 15 the tongue 50 into engagement with its back contact, thereby opening the line circuit, when the condensers are charged through the relay winding.

A better understanding of the system can 20 be obtained from a description of the operation of the system incident to the selection and transmission of a particular character combination. Let it be assumed that the combination of impulses representing the 25 character D is to be transmitted by the automatic transmitter B, and let it be further assumed that the combination of signaling impulses to be set up by the transmitter for representing the character D is current, no 30 current, no current, current, no current. (Obviously other signaling units may be employed if desired.) Therefore, transmitter contacts 10 and 13 will be closed to partially prepare circuits from battery 53 to condensers 30 and 33. The condensers, 35 however, will not be charged at this moment because the switch contacts 25 and 28 are open. With the key 87 closed a circuit is completed from grounded battery 53, 40 switch contact 21, armature 48 of lock-out relay 46 and back contact thereof, charging magnet 44, switch contact 47, segment 48, brush 49, ring 67, to ground. The energization of magnet 44 performs two 45 functions. First, by attracting armature 68 a circuit is completed through the sending start relay 69 from grounded battery 70, relay 69, armature 68 of magnet 44 to ground; and secondly, by bringing contact switches 50 25, 26, 27, 28 and 29 into engagement with their front contacts charging circuits are 55 established for condensers 30 and 33. The charging circuits for the condensers, however, are maintained only temporarily because the energization of relay 69, in addition to bringing armature 72 into engagement with its front contact to close an engaging circuit through start magnet 73, also attracts armature 71 and thereby opens the 60 energizing circuit of magnet 44 at contact 47. Armature 71 and switch contact 47 form a make-before-break contact, thereby maintaining relay 69 in its energized position until brush 49 passes off of segment 48. Upon 65 the energization of start magnet 73, holding

pawl 74 is withdrawn from engagement with brush arm 45 and the brush arm starts to rotate due to its frictional engagement with a constantly rotating shaft.

With the distributor arm at rest, as illustrated in the drawing, brush 75 interconnects segment 65 with ring 42, thereby completing a circuit through the polar line relay 51 which tends to hold the tongue 50 into engagement with contact 41, thereby closing the line circuit. Immediately after the brush arm is released and the brush 75 passes off of segment 65 and on to segment 66 the direction of flow of current through relay 51 is changed due to the discharge of condenser 88 (which condenser has previously been charged as will presently appear), so that the armature tongue 50 moves into engagement with its back contact, thereby opening the line circuit. The instant brush 75 engages segment 60 the condenser 30, which has been charged, will discharge through the winding of relay 51 and thereby throw tongue 50 into engagement with contact 41 to again close the line circuit. The instant brush 75 passes on to segment 61 current will flow from battery 54 through the winding of relay 51 to charge condenser 31, and the charging current through relay 51 will be in a direction tending to throw 95 tongue 50 into engagement with its back contact. The same condition will exist while brush 75 engages segment 62, that is, current will flow from battery 54 through relay 51 to charge condenser 32, thereby 100 holding tongue 50 into engagement with its back contact and maintaining the line circuit open. The instant brush 75 engages segment 63, however, condenser 33 will discharge through the winding of relay 51 and 105 the direction of flow will be such as to bring tongue 50 into engagement with contact 41, thereby closing the line circuit. When brush 75 passes on to segment 64, current, 110 in flowing from battery 54 through the winding of relay 51 to charge condenser 34, will cause the relay tongue 50 to engage its back contact, thereby opening the line circuit.

Since sending start relay 69 was deenergized when brush 49 passed off of segment 48, its armature 72 will be in engagement with its back contact when brush 75 engages segment 65 and thereby establish a circuit through relay 51 which will close the 120 line circuit through relay tongue 50 and contact 41. Armature 72 of relay 69, by moving away from its front contact, opened the energizing circuit of start magnet 73, thereby releasing the detent 74 and permitting it to fall back into position to engage the arm 45 upon completion of the revolution.

During the cycle of operation just described brush 49 interconnected ring 67 with 130

segment 76, thereby establishing a circuit through the tape control magnet 77 from grounded battery 78, winding of magnet 77, switch contact 23, segment 76, brush 49, ring 67, to ground. It is desirable that the transmitter be operated to set up a new character combination as early in the cycle as possible in order that the transmitter contacts may have ample time to settle and 10 store the new character combination. Thus, it will be seen that, as soon as a particular character combination has been set up and stored in the signal storage devices and the circuits from the transmitter contacts to the 15 signal storage devices are opened by the de-energization of charging magnet 44, the transmitter tape control mechanism may be operated.

In the storage and transmission of the 20 character signals just described it has been assumed that predetermined ones of the condensers have been discharged sequentially by the operation of the distributor through the winding of a polar line relay, while the 25 remaining condensers have been charged sequentially through the winding of the polar relay by the operation of the distributor. It is therefore necessary that those condensers which have been charged in transmitting the last character combination be 30 discharged before storing a new character combination. For this purpose a local segment 79 is located on the distributor face so that immediately after the transmission 35 of the last impulse of the character group a circuit may be completed from grounded battery 80, energizing winding of lock-out relay 46, discharging magnet 24, segment 79, brush 49, ring 67, to ground. The energization of magnet 24 connects all the condensers to ground through the switch contacts 35 to 39 inclusive, thereby permitting those condensers in which impulses are 40 stored to discharge. The energization of magnet 24 also attracts armature 89 and stores an impulse in condenser 88 which will be utilized during the next cycle to operate relay 51.

The operation of the system when using 50 the keyboard transmitter is substantially the same as the operation described above in connection with the tape transmitter, except that when employing the keyboard transmitter A the contact switches 15 to 23 inclusive are moved out of engagement with their upper contacts and into engagement with their lower contacts and an overlap relay 81 is operated to prevent repetition of characters in the event a key is held depressed for a period of time greater than the time required for the brush arm to make one revolution and also to prevent the mutilation of character combinations in case two keys are depressed in rapid succession. 60 It will be seen that, when a key of the key-

board (not shown) is depressed to selectively close the switch contacts 55 to 59 inclusive, and switch contact 82, a circuit will be established from grounded battery 83, switch contact 82, switch contact 22, overlap magnet 81, armature 43 of lock-out relay 46 and through the charging magnet 44, as hereinbefore traced. It will also be seen that by means of relay armatures 84 and 85 and locking winding of relay 46, if any key of 75 the keyboard is held depressed until the distributor brush 49 engages segment 79 and operates relay 46, the relay 46 will lock up and thereby hold open the energizing circuit of magnet 44 until the depressed key is 80 released. It will also be seen that if the key first depressed is released and a second key is depressed before the character combination set up by the depression of the first key is transmitted, the locking circuit 85 of relay 46 will be open at armature 84 of overlap relay 81 and the lock-out relay 46 will not be locked to interfere with the starting circuit for the second character.

In the line circuit L is shown a line relay 86 which may be employed to control the operation of a home recording instrument, for example, a printer. A plurality of such relays may be employed at as many different receiving stations for operating 95 suitable receiving instruments as fully disclosed in copending application Serial No. 176,390, filed June 22, 1917.

What is claimed is:

1. In a selecting system, a line circuit, an 100 electro-responsive device for controlling said line circuit, electrical storage devices, character determining elements for storing electrical impulses in said devices in predetermined combinations, and a distributor for 105 utilizing the stored impulses and for storing additional impulses in those devices which were unaffected by said character determining elements to operate said electro-responsive device.

2. In a selective signaling system, a plurality of electrical storage devices, a plurality of character determining elements, means controlled by said character determining elements for storing electrical impulses in said devices in different combinations, a circuit including a responsive device, and means for utilizing the stored impulses and for storing additional impulses in said storage devices to operate said responsive device.

3. In a selective signaling system, a circuit including a responsive device, a plurality of electrical storage devices, means for simultaneously storing electrical impulses in predetermined ones of said storage devices, and means for storing electrical impulses in the remaining ones of said devices, said means directing the passage of all said impulses through said circuit to operate the responsive device.

4. In a selecting system, a plurality of condensers included in normally open circuits, selectively operable means for controlling the charging of said condensers in various permutations, and an electromagnet controlled by said selectively operable means for simultaneously completing the charging circuits to the condensers.
5. In a selective signaling system, a plurality of condensers, means for charging predetermined ones of said condensers with current of a given polarity, character determining elements controlling the charging of said condensers, a circuit including a responsive device, and a distributor for discharging said charged condensers and for charging the discharged condensers sequentially through said responsive device.
6. In a selective signaling system, a plurality of condensers, selectively operable switches for controlling the charging of said condensers in various combinations depending upon the signal to be transmitted, a circuit including a responsive device, and means for discharging said charged condensers and for charging the uncharged condensers sequentially through said responsive device.
7. In a selective signaling system, a plurality of normally discharged condensers, means for charging predetermined ones of said condensers with one polarity, means for charging the remaining ones of said condensers with a different polarity, and a circuit including a responsive device, said responsive device being controlled by the discharging of the predeterminedly charged condensers and by the charging of the last-mentioned condensers.
8. In a selective signaling system, a plurality of condensers, selectively operable means for charging predetermined ones of said condensers with one polarity, a responsive device, and means controlled by said selectively operable means for discharging the charged condensers and for charging the remaining condensers sequentially through said responsive device.
9. In a selective signaling system, a plurality of condensers, character determining elements for charging predetermined ones of said condensers, means for discharging said charged condensers and for charging the remaining condensers of the group, and means controlled by said last-mentioned means for discharging the remaining ones of said condensers.
10. In a selective signaling system wherein each character transmitted is represented by a different permutation of current impulses, a set of selectively operable switches for determining the character to be transmitted, a group of normally discharged condensers, means under the control of said switches for charging predetermined ones of said condensers, a circuit, and means for discharging said charged condensers and for charging the remaining condensers of said group sequentially through said circuit.
11. In a telegraph transmitter, a line circuit, a relay controlling said line circuit, a plurality of condensers, means for charging predetermined ones of said condensers with one polarity, and means for successively discharging said charged condensers and for charging the remaining ones of said condensers with current of opposite polarity through the said relay to operate the same.
12. The combination with a plurality of condensers, of means for charging predetermined ones of said condensers simultaneously, a responsive device, means acting sequentially to discharge said charged condensers and to charge said other condensers through said responsive device, and means for simultaneously discharging said sequentially charged condensers.

In witness whereof, I hereunto subscribe my name this 1st day of June, A. D., 1918.

ANDREW D. DOWD.
